CLAIM

The ornamental design for a liquid warmer, as shown and described.

DESCRIPTION

FIG. 1 is a perspective view of a first embodiment of my ornamental design for the liquid warmer including three bands;

FIG. 2 is a back view of the ornamental design of the embodiment of FIG. 1;

FIG. 3 is a front view of the ornamental design of the embodiment of FIG. 1;

FIG. 4 is a left side view of the ornamental design of the embodiment of FIG. 1;

FIG. 5 is a right side view of the ornamental design of the embodiment of FIG. 1;

FIG. 6 is a top view of the ornamental design of the embodiment of FIG. 1;

FIG. 7 is a bottom view of the ornamental design of the embodiment of FIG. 1;

FIG. 8 is a front perspective view of the ornamental design of the embodiment of FIG. 1 when the liquid warmer is unwrapped;

FIG. 9 is a front view of the ornamental design of the embodiment of FIG. 1 when the liquid warmer is unwrapped;

FIG. 10 is a back view of the ornamental design of the embodiment of FIG. 1 when the liquid warmer is unwrapped;

FIG. 11 is a side view of the ornamental design of the embodiment of FIG. 1 when the liquid warmer is unwrapped and the front of the liquid warmer is facing up;

FIG. 12 is another side view of the ornamental design of the embodiment of FIG. 1 when the liquid warmer is unwrapped and the back of the liquid warmer is facing up;

FIG. 13 is another side view of the ornamental design of the embodiment of FIG. 1 when the liquid warmer is unwrapped and the front of the liquid warmer is facing down;

FIG. 14 is another side view of the ornamental design of the embodiment of FIG. 1 when the liquid warmer is unwrapped and the front of the liquid warmer is facing up;

FIG. 15 is a perspective view of a second embodiment of my ornamental design for my liquid warmer including two bands;

FIG. 16 is a back view of the ornamental design of the embodiment of FIG. 15;

FIG. 17 is a front view of the ornamental design of the embodiment of FIG. 15;

FIG. 18 is a left side view of the ornamental design of the embodiment of FIG. 15;

FIG. 19 is a ride side view of the ornamental design of the embodiment of FIG. 15;

FIG. 20 is a top view of the ornamental design of the embodiment of FIG. 15;

FIG. 21 is a bottom view of the ornamental design of the embodiment of FIG. 15;

FIG. 22 is a front perspective view of the ornamental design of the embodiment of FIG. 15 when the liquid warmer is unwrapped;

FIG. 23 is a front view of the ornamental design of the embodiment of FIG. 15 when the liquid warmer is unwrapped;

FIG. 24 is a back view of the ornamental design of the embodiment of FIG. 15 when the liquid warmer is unwrapped;

FIG. 25 is a side view of the ornamental design of the embodiment of FIG. 15 when the liquid warmer is unwrapped and the front of the liquid warmer is facing up;

FIG. 26 is another side view of the ornamental design of the embodiment of FIG. 15 when the liquid warmer is unwrapped and the back of the liquid warmer is facing up;

FIG. 27 is another side view of the ornamental design of the embodiment of FIG. 15 when the liquid warmer is unwrapped and the front of the liquid warmer is facing down;

FIG. 28 is another side view of the ornamental design of the embodiment of FIG. 15 when the liquid warmer is unwrapped and the front of the liquid warmer is facing up;

FIG. 29 is a perspective view of a third embodiment of my ornamental design for my liquid warmer including one band;

FIG. 30 is a back view of the ornamental design of the embodiment of FIG. 29;

FIG. 31 is a front view of the ornamental design of the embodiment of FIG. 29;

FIG. 32 is a left side view of the ornamental design of the embodiment of FIG. 29;

FIG. 33 is a ride side view of the ornamental design of the embodiment of FIG. 29;

FIG. 34 is a top view of the ornamental design of the embodiment of FIG. 29;

FIG. 35 is a bottom view of the ornamental design of the embodiment of FIG. 29;

FIG. 36 is a front perspective view of the ornamental design of the embodiment of FIG. 29 when the liquid warmer is unwrapped;

FIG. 37 is a front view of the ornamental design of the embodiment of FIG. 29 when the liquid warmer is unwrapped;

FIG. 38 is a back view of the ornamental design of the embodiment of FIG. 29 when the liquid warmer is unwrapped;

FIG. 39 is a side view of the ornamental design of the embodiment of FIG. 29 when the liquid warmer is unwrapped and the front of the liquid warmer is facing up;

FIG. 40 is another side view of the ornamental design of the embodiment of FIG. 29 when the liquid warmer is unwrapped and the back of the liquid warmer is facing up;

FIG. 41 is another side view of the ornamental design of the embodiment of FIG. 29 when the liquid warmer is unwrapped and the front of the liquid warmer is facing down; and,

FIG. 42 is another side view of the ornamental design of the embodiment of FIG. 29 when the liquid warmer is unwrapped and the front of the liquid warmer is facing up.
